UNITED STATES PATENT OFFICE.

ROBERT G. CLARK, OF BROOKLYN, NEW YORK.

SHEET-FEEDING MECHANISM.

1,225,410.

Specification of Letters Patent.

Patented May 8, 1917.

Application filed September 4, 1915. Serial No. 48,977.

To all whom it may concern:

Be it known that I, ROBERT G. CLARK, a citizen of the United States, residing in the borough of Brooklyn, in the county of 5 Kings, city and State of New York, have invented new and useful Improvements in Sheet-Feeding Mechanism, of which the following is a specification.

This invention relates to mechanism to 10 separate and feed sheets or blanks from a pile to mechanism to operate upon such sheets or blanks, and it is the object of the invention to provide a mechanism of this character which is simple and cheap in construction and efficient in operation, and which may be constructed as an attachment to be applied to machines for operating upon the separated and fed sheets.

While I have shown in the drawings an 20 embodiment of my invention as adapted to separate and feed metallic sheets or blanks from a pile to be utilized as the blank feeding mechanism of a can body forming or can making machine, it is to be understood 25 that it is applicable to other types of apparatus and to feed other than metallic sheets or blanks.

In carrying out the invention I provide 30 a carriage to reciprocate beneath a pile of sheets or blanks, said carriage having means to engage with and move the lowermost sheet of the pile against an abutment to buckle the sheet, fingers pivoted on and movable with the carriage engaging with 35 the buckled portion of the sheet when the carriage is moved in a reverse direction to separate and feed the sheet from the pile.

In the drawings accompanying and forming 40 a part of this specification, Figure 1 is a plan view of the rear portion of the framework of a can body forming machine illustrating an embodiment of my invention applied thereto.

Fig. 2 is a sectional side elevation taken 45 substantially on the lines A—A of Fig. 1.

Fig. 3 is a perspective view partly broken away and looking at the rear of the machine; and

Figs. 4 to 6 are enlarged sectional side

elevations taken substantially on the line 50 B—B of Fig. 1 and showing different positions of the sheet separating and feeding means.

Similar characters of reference designate like parts throughout the different views of 55 the drawings.

In the drawings I have shown an embodiment of my invention in connection with a can body forming machine and as applied to the rear of the framework F 60 thereof. A pile of sheets or blanks S is supported adjacent its side edges upon bars 7, 7 fixed to the framework and centrally thereof upon a bar 8 fixed to a reciprocable carriage 9. The sheets are confined between 65 vertical side members 10 and at the front edges by bars 11 carried by a cross bar 12 fixed at its ends to brackets 13 mounted on the framework. The lower ends of the bars 11 are free and extend to a point slightly 70 below the lowermost sheet of the pile. The rear edges of the sheet are confined by a vertical bar 14 adjustably carried by a cross bar 15 by a bolt 16 engaging in an opening 17 in said bar, the cross bar being fixed 75 at its ends to brackets 18 fixed to the framework, the side bars 10 also being fixed to the cross bar 15. The lower end of the bar 14 is free and extends to a point so that it will be above and clear the lowermost sheet 80 of the pile as clearly shown in Figs. 2 and 3 for a purpose to be hereinafter described.

The support 8 is carried by and reciprocated with the carriage 9 which is actuated by a crank 19 on a shaft 20 operated 85 from any suitable source, such as the main driving shaft of the machine, (not shown), the carriage being connected to the crank by a rod 21. It will be understood that the reciprocation of the carriage is so timed 90 that it will operate in proper timed sequence with the mechanism which operates upon the fed blanks or sheets.

During the latter operation of the rearward movement of the carriage and support 8 a dog 22, which is in the nature of a starting dog for the sheets, adjustably secured by screw 23 to the top of the support

8 and having its forward edge beveled or inclined as shown, engages with the front edge of the lowermost sheet and forces said sheet rearward for a predetermined distance, the rear edge of the sheet during this movement engaging with a bevel or cam face 24 on the lower end of abutments 25 in the form of bars carried by the cross bar 15. The abutments extend to a point below the upper surface of the central support 8 and the bevel extends downward and rearward being at a point above and clearing the lowermost sheet of the pile. As the sheet passes below the abutments it is buckled or bent from the front to the rear edge at opposite sides of the central support 8, such buckled portion of the sheet engaging bars 26, 26 fixed to the carriage preventing the ends of the sheets from springing from the side support 7. In the extreme rear position of the carriage the rear edge of the sheet will extend slightly beyond the bottom of the abutments as clearly shown in Figs. 3 and 4, and the sheet is maintained in this position during the initial forward movement of the carriage and until they are engaged and pushed forward by resilient fingers 27. These fingers are pivotally supported at 28 upon the bars 26 and the forward ends are forced upward by springs 29, such ends in the rearward position of the carriage engaging under projections 30 extending rearwardly from the abutments 25. During the initial forward movement of the carriage these forward ends ride along said projections until they strike a bevel or cam face 31 on the abutments opposite to the cam faces 24 with the extremities of the fingers above the rear portion of the sheet. During the further forward movement of the carriage the forward ends of the fingers will ride down the cam faces 31 with the under surface of an under cut portion of the fingers resting on the top of the sheet, when the fingers will ride under the abutments and along the upper surface of the sheet, separating said sheet from the pile (as shown in Fig. 5) and until a shoulder 33 formed by the under cut portions engages with the rear edge of the sheet when the sheet is moved forward with the fingers, the lateral ends being buckled or bent over the central support 8 will readily clear the bottom of the bars 11, the fingers 27 being of such length so that the under faces of the abutments 25 will engage with the fingers during the movement of the fingers under the stops 11. During the continued forward movement the central portion of the sheet will ride up the inclined rear ends on guides 34 until it rests in its buckled condition upon a flat portion on said guides, as shown in Fig. 2, the pressure of the fingers on said sheet being then released by the springs 29, forcing the fingers upward into

engagement with the extensions 30 of the abutments 25, as shown in Fig. 6, when the carriage is returned and the next sheet is engaged by the dog 22 to repeat the operation.

The guide 34 is in the form of a pair of plates engaging at opposite sides of the central support 8 with the flat portion extending a distance somewhat above the dog 22, thereby permitting the return movement of said dog without interfering with a fed sheet. Upon the next forward movement of the carriage dogs 35 carried by the bars 26 will engage the sheet on the guides moving it down the forward inclined portion of the guides 34 to the position shown at S' in Fig. 2 where it may be taken up by the means to operate upon the sheet.

By the adjustable supporting of the bar 14 in a vertical direction the device is adapted for sheets of different thickness. It will be obvious that by adjusting said bar so that the bolt will be in the lowermost portion of the opening 17 it will be adapted for thin sheets, and to utilize the device for feeding sheets of greater thickness the bar is adjusted upwardly. During the forward movement of the sheet it is guided between the guides 36, 36.

Having thus described my invention I claim:

1. In a sheet feeder, the combination of a support for a pile of sheets; a reciprocable carriage; means on said carriage to engage with and move a sheet from the pile when moving in one direction; means to engage with and buckle said sheet during said movement thereof; and means on said carriage to engage with the buckled portion of the sheet when the carriage is moved in reverse direction to separate and feed the sheet from the pile.

2. In a sheet feeder, the combination of a support for a pile of sheets; a reciprocable carriage; means on said carriage to engage with one edge of a sheet and move it from the pile when moving in one direction; means to engage with the opposite edge of the sheet and buckle the same during said movement of the sheet; and means on said carriage to engage with the buckled portion of the sheet when the carriage is moved in reverse direction to separate and feed the sheet from the pile.

3. In a sheet feeder, the combination of means to support a pile of sheets adjacent the sides; a reciprocable support for the central portion of the sheets; means carried by said support to engage with and move a sheet from the pile when moved in one direction; means to buckle said sheet during said movement thereof; and means carried by said support to engage with and separate said sheet from the pile when the support is moved in a reverse direction.

4. In a sheet feeder, the combination with a support for a pile of sheets, of a reciprocable carriage; a dog movable with the carriage to engage with and move the lowermost sheet from the pile for a predetermined distance when the carriage is moved in one direction; means to engage with and buckle said sheet during said movement; and fingers movable with the carriage to engage over the buckled portion of the sheet when the carriage is moved in a reverse direction to separate and feed the sheet from the pile. 70
5. In a sheet feeder, the combination with a support for a pile of sheets, of a reciprocable dog to engage with the lowermost sheet of the pile and move it a predetermined distance in one direction; an abutment with which said sheet engages during said movement to buckle the same; and fingers movable with the dog to engage with the buckled portion of said sheet when the dog is moved in a reverse direction to separate and feed the sheet from the pile. 75
- 10 6. In a sheet feeder, the combination with a support for a pile of sheets, of a reciprocable dog to engage with one edge of the lowermost sheet of the pile and move it a predetermined distance when moved in one direction; a pair of abutments to engage with the opposite edge of said sheet as it is moved by the dog to buckle the sheet on opposite sides of the center thereof; and a pair of fingers movable with the dog to engage the buckled portions of the sheet when the dog is moved in a reverse direction to separate and feed the sheet from the pile. 80
- 15 7. In a sheet feeder, the combination with a support for a pile of sheets, of a reciprocable carriage; a dog movable with the carriage to engage one edge of the lowermost sheet of the pile and move said sheet a predetermined distance when the carriage is moved in one direction; a pair of abutments having cam faces with which the opposite end of the sheet engages during the said movement of the sheet to buckle the sheet at opposite sides of the center thereof; and a pair of resilient fingers on the carriage to engage the edge and above the buckled portions of the sheet when the carriage moves in a reverse direction to separate and feed the sheet from the pile. 85
- 20 8. In a sheet feeder, the combination with a support for a pile of sheets, of a reciprocable carriage; a dog movable with the carriage to engage one edge of the lowermost sheet of the pile and move said sheet a predetermined distance when the carriage is moved in one direction; a pair of abutments having cam faces with which the opposite edge of the sheet engages during the said movement of the sheet to buckle the sheet at opposite sides of the center thereof; a pair of resilient fingers on the carriage to engage the edge and above the buckled portions of the sheet 90
- 25 and move it a predetermined distance when the carriage is moved in one direction; means to engage with the buckled portions of the sheet to separate and feed the sheet from the pile when the carriage is moved in a reverse direction. 95
- 30 9. In a sheet feeder, the combination of a support to support a pile of sheets adjacent opposite sides; a reciprocable carriage; a bar fixed to and movable with the carriage to support the pile of sheets centrally thereof; a dog fixed to said bar to engage with one edge of the lowermost sheet of the pile and move said sheet a predetermined distance when the carriage is moved in one direction; a pair of abutments having a cam face to engage the edge of the sheet opposite to that with which the dog engages during the said movement of the sheet to buckle the sheet at opposite sides of the bar; and fingers resiliently mounted on the carriage to engage with the buckled portions of the sheet to separate and feed the sheet from the pile when the carriage is moved in a reverse direction. 100
- 35 10. In a sheet feeder, the combination of a support to support a pile of sheets adjacent opposite sides; a reciprocable carriage; a bar fixed to and movable with the carriage to support the pile of sheets centrally thereof; a dog fixed to said bar to engage with one edge of the lowermost sheet of the pile and move said sheet a predetermined distance when the carriage is moved in one direction; a pair of abutments having cam faces to engage with the edge of the sheet 105
- 40 opposite to that with which the dog engages during said movement of the sheet to buckle the sheet at opposite sides of the bar, said abutments having rearward projections; a pair of fingers pivotally mounted on the carriage with the free ends normally engaging below the abutment projections; springs to force said fingers upward; said fingers engaging with the edge and above the buckled portions of the sheet when the carriage is moved in a reverse direction to separate and feed the sheet; and a second cam face on said abutments with which said fingers engage to cause them to clear the next adjacent sheet of the pile. 110
- 45 11. In a sheet feeder, the combination of a support to support a pile of sheets adjacent opposite sides and centrally thereof; means to move the lowermost sheet of the pile a predetermined distance in one direction and 115
- 50 buckle said sheet at opposite sides of the central support; and fingers to engage with the buckled portions of said sheet to move it in an opposite direction to separate and feed the sheet from the pile. 120
- 55 12. In a sheet feeder, the combination of a support for a pile of sheets; means to engage and move the lowermost sheet a predetermined distance from the pile and simultaneously buckle said sheet at different 125
- 60 65 70 75 80 85 90 95 100 105 110 115 120 125 130

points; and means to engage with the buckled portions of the sheet to move it in a reverse direction to separate and feed the sheet from the pile.

5 13. In a sheet feeder, the combination of a support for a pile of sheets; a reciprocable dog to engage with and move the lowermost sheet a predetermined distance from the pile; abutments with which said sheet en-

gages during said movement to buckle the sheet; resilient fingers movable with the dog to engage with the buckled portions of the sheet to move it in a reverse direction to separate and feed the sheet from the pile; and a guide over which said sheet is moved to permit the return of the dog, substantially as and for the purpose specified.

ROBERT G. CLARK.
